CLAIM

The ornamental design for housings for air conditioning apparatus, as shown and described.

DESCRIPTION

FIG. 1 is a perspective view of one embodiment of the housings for air conditioning apparatus;

FIG. 2 is a front view of the housings for air conditioning apparatus;

FIG. 3 is a rear view of the housings for air conditioning apparatus;

FIG. 4 is a right side view of the housings for air conditioning apparatus;

FIG. 5 is a left side view of the housings for air conditioning apparatus;

FIG. 6 is a top view of the housings for air conditioning apparatus; and,

FIG. 7 is a bottom view of the housings for air conditioning apparatus.

The broken lines showing of items in FIG. 6 depict portions of the article that form no part of the claimed design.
